UNITED STATES PATENT OFFICE.

JOHN A. MITCHELL, OF NEWARK, NEW JERSEY, ASSIGNOR OF ONE-HALF TO A. D. T. LIBBY, OF EAST ORANGE, NEW JERSEY.

DEVICE FOR MIXING MATERIALS.

Application filed January 18, 1922. Serial No. 530,071.

To all whom it may concern:

Be it known that I, JOHN A. MITCHELL, a citizen of the United States, residing at Newark, in the county of Essex, State of New Jersey, have invented certain new and useful Improvements in a Device for Mixing Materials, of which the following is a description, reference being had to the accompanying drawing and to the figures of reference marked thereon.

This invention relates to a device for mixing materials, such as paints, varnish, syrup and such like. In mechanical mixers of which I am aware, a propeller is carried on a shaft which telescopes a projecting end of an operating shaft, some fastening means being provided to hold the propeller shaft in the position in which it is set with respect to the drive shaft. This fastening means together with the propeller shaft and the drive shaft extension are all in the vat or container and, therefore, always covered with the mixture so that when the height of the propeller in the vat or container is desired to be changed, the aforesaid fastening means is all covered with varnish, paint or syrup or whatever is being mixed, thereby causing the fastening means to stick together and making the job of adjusting the propeller shaft length a disagreeable one.

It is the principal object of my invention to provide a design of mixer in which this difficulty is overcome. I do this by providing a hollow drive shaft suitably mounted in a housing and extending the propeller shaft all the way through the hollow drive shaft and then use attaching means between the hollow shaft and the propeller shaft on that end of the drive shaft away from the vat or container. This construction leaves the said fastening means always clean and easily and quickly gotten at.

Furthermore the propeller shaft may be quickly raised and lowered to any desired height without the operator getting his hands into the material that is being mixed.

Another object of my invention is to provide means for quickly attaching the mixer to the container carrying the material to be mixed and further to provide means for swinging the propeller shaft to any desired angle within the container.

These and other objects will be clearly apparent from a reading of the specification

taken in connection with the drawing, 55 wherein:

Figure 1 shows my mixer attached to a vat or container for large industrial purposes;

Figure 2 is a part sectional plan view through the housing carrying the drive 60 shaft, as well as the means for operating the drive shaft;

Figure 3 is a view of one form of means for attaching the mixer to a container;

Figure 4 is a view of a detail part used 65 to connect the mixer with the attachment means shown in Fig. 3;

Figure 5 is an end view of Fig. 4;

Figure 6 is a fragmentary view of a support on the housing which carries the hollow 70 drive shaft;

Figure 7 is an end view of Fig. 6;

Figure 8 is a detailed view of the hollow drive shaft showing the stuffed gland on one end and means for fastening the drive shaft 75 to the hollow shaft on the other; and

Figure 9 is a view of a smaller device than that shown in Fig. 1, to illustrate how certain of the details may be readily modified.

Referring now to the details wherein like numbers refer to corresponding parts in the various views, 1 is a vat or container for carrying the materials to be mixed. The mixer itself consists of a housing 2 which 80 may be made in any suitable form or number of parts, but will be herein generally referred to as the housing. Carried on the housing 2 is a hollow shaft 3, which may have any suitable bearings, ball bearings 4 85 90 being illustrated in Fig. 2.

The hollow shaft 3 projects through the housing at both ends and has preferably at the end toward the container a stuffing gland 5 for the purpose of guiding the propeller shaft 6 and also preventing any grease or oil, if any be used, working out of the housing 2. Since ball bearings are used, substantially no oil need be placed thereon, so that there is substantially no danger of 100 any oil getting by the stuffing gland 5. On the other end of the hollow shaft 3 or that end away from the container 1, suitable fastening means is used to grip the propeller shaft 6 in any desired position to which it 105 is adjusted in a longitudinal direction with respect to the hollow shaft 3. The fastening means shown is in the form of a chuck 7,

the same as used on a machinist lathe. On the end of the shaft 6 is carried a propeller 8 which may have as many blades as desired.

The housing 2 has hollow supports 9, one of which terminates in a circular flange 10. Flange 10 has a series of holes 11 which cooperate with a pin 12 carried on a flange 13. The pin 12 is operated by a knob 14 against the action of a spring 15, so that the pin 12 may be withdrawn from the holes 11, whereby the housing 2 and the two shafts may be adjustably rotated through an angle to move the propeller into some other portion of the container 1. When the desired angle is attained, the pin 12 is released and sets within one of the holes 11, thereby locking the two flanges 10 and 13 together. It will be understood that the pin 12, knob 14 and spring 15 may be carried in the flange 10 and 20 the holes 11 in the flange 13. The flange 13 is securely fastened to a rod 16, whose end 17 passes within the hollow portion 18 of the support 9, thereby giving a bearing for the supports 9. The rods 16 may be solid, 25 but I prefer to use a hollow tube as shown in Fig. 4 in order to lighten up the device. These rods 16 are adjustably fastened to attachment means 19 by set screws 20, locking screws 21 being used for fastening the attachment means 19 to the rim of the container 1. It will be seen that the attachment means 19 may be slid around on the container to any desired position, after which the locking screws 21 are set up and the set 35 screws 20 fastened in position.

One means for driving the hollow shaft 3 is illustrated in Fig. 2 by means of a gear wheel 22, which in my preferred form is geared to another gear wheel 23 that is preferably operated by an electric motor, the housing for which is illustrated by 24.

In Fig. 9 the attachment means between the propeller and hollow shafts are similar to that shown in Fig. 1 and since the other 45 details are clearly apparent they will not be further discussed herein.

It will be seen from the above description that I have provided a complete unitary as well as sanitary mixing structure, in 50 which preferably a relatively high speed motor of small size is geared to give the proper reduction to a propeller shaft through the medium of the devices described.

The device is quickly adapted to any size 55 of vat or container and may be quickly set at any angle. It will be apparent to those skilled in the art that numerous changes may be made in the details without departing from the spirit of my invention and the 60 scope of the appended claims.

Having thus described my invention, what I claim is:

1. In a device of the class described, a hollow shaft and bearings therefor, means 65 for driving said shaft, a propeller shaft

passing clear through said hollow shaft and means for fastening the propeller shaft to the hollow shaft in any desired longitudinal position.

2. In a device of the class described, a 70 hollow shaft and bearings therefor, means for driving said shaft, a propeller shaft passing clear through said hollow shaft and a quickly operative chuck for adjusting and fastening the propeller shaft in any desired 75 longitudinal position.

3. In a device of the class described, a housing, a hollow shaft and bearings therefor carried by said housing, a gear wheel on said shaft, a motor geared to said gear wheel, a shaft, carrying a propeller, passing clear through said hollow shaft and means 80 for readily adjusting and securing the position of the propeller and its shaft with respect to the hollow shaft.

4. In a device of the class described, a hollow shaft and bearings therefor, means for driving said shaft, a propeller shaft passing clear through said hollow shaft, means for fastening the propeller shaft to the hollow shaft in any desired longitudinal position, and further means for swinging both said shafts through an angle in the plane of said shafts.

5. In a device of the class described, a housing, a hollow shaft and bearings therefor carried by said housing, a gear wheel on said shaft, a motor geared to said gear wheel, a shaft, carrying a propeller, passing clear through said hollow shaft, means for 100 readily adjusting and securing the position of the propeller and its shaft with respect to the hollow shaft, and further means for swinging said housing, motor and shafts, through an angle in the plane of said shaft. 105

6. In a device of the class described, a housing, a hollow shaft and bearings therefor carried by said housing, a gear wheel on said shaft, a motor geared to said gear wheel, a shaft, carrying a propeller, passing 110 clear through said hollow shaft, a stuffing gland on one end of the hollow shaft and a chuck on the other end of the hollow shaft for gripping the propeller shaft at any desired point.

7. A device for mixing materials in a container, consisting of, a housing, a hollow shaft carried by the housing, means for driving said shaft, a shaft, carrying a propeller, passing through said hollow shaft and means carried by the hollow shaft on the end away from the container for securing the propeller shaft to the hollow shaft in any desired longitudinal position with respect thereto.

8. A device for mixing materials in a container, consisting of, a housing, a hollow shaft carried by the housing, means for driving said shaft, a shaft carrying a propeller passing through said hollow shaft, a 130

stuffing gland on that end of the hollow shaft toward the container, and a chuck carried by the hollow shaft on the end away from the container for adjustably 5 securing the propeller shaft to the hollow shaft.

9. A device for mixing materials in a container, consisting of, a housing having a support or supports, a hollow shaft extending 10 through the housing and having bearings thereon, means for driving said shaft, a shaft, carrying a propeller, passing all the way through said hollow shaft, means outside the container for fastening the propeller shaft to the hollow shaft in any desired 15 longitudinal position, attachment means to go on the container, and means connecting said attachment means to said housing support or supports.

10. A device for mixing materials in a container, consisting of, a housing, having a support or supports, a hollow shaft extending through the housing and having bearings thereon, means for driving said shaft, a 20 shaft, carrying a propeller, passing all the way through said hollow shaft, means outside the container for fastening the propeller shaft to the hollow shaft in any desired longitudinal position, attachment means to go on the container, means connecting 25 said attachment means to said housing support or supports, and means interposed between said connecting means and said support or supports for swiveling said 30 housing and shafts through an angle.

11. A device for mixing material in a container, consisting of, a housing, having a support or supports, a hollow shaft extending through the housing and having bearings thereon, means for driving said shaft, a 40 shaft, carrying a propeller, passing all the way through said hollow shaft, means outside the container for fastening the propeller shaft to the hollow shaft in any desired longitudinal position, adjustable attachment means to go on the container, a flange 45 on one of said housing supports, a second flange adjustably fastened to said attachment means and means associated with said flanges for permitting one to be rotated 50 with respect to the other and then locking them together.

12. In a device of the class described, adjustable attachment means for engaging the rim of a container, members adjustably carried by said attachment means and extending toward each other above the top of the container, a housing having supports for engaging said members, a hollow shaft carried by said housing and extending therethrough, a propeller shaft passing through said hollow shaft, a chuck on the outer end of the hollow shaft for gripping the propeller shaft, a gear wheel fastened to the hollow shaft and a motor operatively carried by the 60 housing and drivingly connected to said gear wheel.

In testimony whereof I affix my signature.

JOHN A. MITCHELL.
